US0D1026738S

(12) **United States Design Patent** (10) **Patent No.:** **US D1,026,738 S**
(45) **Date of Patent:** **** May 14, 2024**

(54) **BICYCLE**

(71) Applicant: **Woom GmbH**, Klosterneuburg (AT)

(72) Inventor: **Matthias Leite-Gürtner**, Vienna (AT)

(73) Assignee: **WOOM GMBH**, Klosterneuburg (AT)

(**) Term: **15 Years**

(21) Appl. No.: **29/899,363**

(22) Filed: **Aug. 8, 2023**

Related U.S. Application Data

(62) Division of application No. 35/514,223, filed on Feb. 17, 2022 (U.S. filing date under 35 U.S.C. 384), and having an international filing date of Feb. 17, 2022, now Pat. No. Des. 1,001,019.
